US0D1004777S

(12) **United States Design Patent** (10) **Patent No.:** **US D1,004,777 S**
(45) **Date of Patent:** **** Nov. 14, 2023**

(54) **WRIST READER**

(71) Applicant: **TT1 Products, Inc.**, Atlanta, GA (US)

(72) Inventors: **Justin Arsenault**, Atlanta, GA (US);
Ryan Sanderson, Atlanta, GA (US);
Todd Furneaux, Atlanta, GA (US);
Harold Philpott Southerland, Atlanta, GA (US)

(73) Assignee: **TT1 Products, Inc.**, Atlanta, GA (US)

(**) Term: **15 Years**

(21) Appl. No.: **29/806,143**

(22) Filed: **Sep. 1, 2021**

(51) LOC (14) Cl. **24-02**

(52) U.S. Cl.

USPC **D24/167; D14/344**

(57) **CLAIM**

The ornamental design for a wrist reader, as shown and described.

DESCRIPTION

FIG. 1 is a perspective view of a wrist reader, showing our new design;

FIG. 2 is another perspective view of the wrist reader;

FIG. 3 is a front view of the wrist reader;

FIG. 4 is a rear view of the wrist reader;

FIG. 5 is a top view of the wrist reader;

FIG. 6 is a bottom view of the wrist reader;

FIG. 7 is a side view of the wrist reader; and,

FIG. 8 is a side view of the wrist reader.

The broken lines shown in the drawings illustrate portions of the wrist reader and form no part of the claimed design.

1 Claim, 8 Drawing Sheets
